SYLVESTER W. CROWLEY, OF WEEHAWKEN, NEW JERSEY, ASSIGNOR TO DE FOREST
RADIO TELEPHONE & TELEGRAPH CO., OF JERSEY CITY, NEW JERSEY, A CORPORA-
TION OF DELAWARE.

ELECTRON-DISCHARGE DEVICE.

Application filed January 7, 1924. Serial No. 684,790.

This invention relates to electron discharge device and more particularly to the plate therein and the mounting for said plate.

The objects of the invention are to provide a substantial plate and mounting so as to eliminate as far as possible vibrations and microphonic action; to provide a structure in which the application of the plate to its support may be readily accomplished; to provide a structure wherein the plate and its support may be fastened together and thus secure both positive electric connection and a rigid construction; to avoid extra parts or utilization of any devices which would have a detrimental effect upon the plate or associated parts; to provide means for strengthening the plate and retaining the same thereby in proper shape; to provide a bulged middle portion of the plate; to thus enable the plate to remain at substantially equal distance throughout its area from the grid; to utilize portions of the plate itself for reinforcing the plate; to thus avoid application of separate reinforcing means; to secure simplicity of construction, operation and assembly; and to obtain other advantages and results as may be brought out in the following description.

Referring to the accompanying drawing in which like numerals of reference indicate similar parts throughout the several views;

Figure 1 is an elevation of an electron discharge device with portions of the bulb broken away disclosing my invention therein;

Figure 2 is a perspective view of the plate;

Figure 3 is a plan view of the plate; and

Figure 4 is a perspective view of the stem and several supports issuing therefrom.

In the specific embodiment of the invention illustrated in said drawing, reference numeral 1 indicates the bulb of an electron discharge device integral with which is a stem 2, the bulb and stem being properly mounted within a base 3. Issuing from the inner end of the stem are a plurality of wires or supports. In the precise showing exemplified in the drawing I have shown a support 4 at the middle of the stem which is offset laterally and is provided at the top with a transverse hook 5. At opposite sides

of the central support 4 are terminal wires 6, 6, to which the ends of a hairpin filament 7 are attached, the looped portion of said filament being supported by hook 5 on support 4. At opposite sides of the filament terminal 6 are two more wires 8, 8, issuing from the stem in the same general plane as the other wires, said wires 8 being offset transversely so as to provide upper parallel ends or prongs 9 which are further apart than the distance between the wires where they issue from the stem, but in the same plane. These prongs 9, 9, support a grid 10, (only a portion of which I have shown). Beyond wires 8, 8, and issuing from the stem are two outside wires 11, 11, likewise in the same plane with the rest of the wires and offset transversely a greater distance than wires 8, 8, so as to provide parallel supports or prongs 12, 12 in the same plane with the other wires and prongs.

Upon these last mentioned prongs 12, 12 is mounted plate 13. Said plate preferably consists of a single piece of metal bent in substantially rectangular formation, open at top and bottom. In one direction the plate is narrow so as to be close to the grid and in the other direction it is wide enough to extend from one of the outside prongs 12 to the other and can be slid downwardly with its end walls between prongs 9 and 12 in engagement with both of the outside prongs 12, 12. Furthermore, the plate is preferably of a height substantially equal to the length of the offset portions or prongs 12, as clearly shown in Figure 1. In order to mount the plate 13 in place, I preferably stamp outwardly from end walls 14, 14, thereof, portions of metal to provide eyelets 15. Said eyelets are arranged so as to be in alignment longitudinally of the said end walls and of sufficient size to permit the prongs 12 to be inserted therein. Accordingly, in assembling the device, the plate is slid downwardly onto prongs 12, 12, with the said prongs passing through the outstanding eyelets on the end walls which are in engagement with said prongs. To complete the assembly, I preferably spot weld the plate upon the prongs, doing this in a number of places, through the eyelets and elsewhere, in order to be assured that there is a positive union between the parts both

for the purpose of preventing the plate from coming off or rattling, and for the purpose of obtaining positive electrical contact.

- In the manufacture of the plate, I preferably weld the seam 16 where the edges of the metal overlap so there will be no opportunity for the plate to spread or for the end portions to spring away from the grid. It is to be observed that the particular shape 10 of the plate which has so far been described provides narrow end walls 14 which cooperate with the larger faces 17 to reinforce the same and prevent bowing at their edges inwardly or outwardly in a vertical direction. 15 In order to retain the shape of the faces 17 in a transverse direction, I preferably bend the top and bottom margins of said faces outwardly as clearly shown in Figure 2 so as to provide outstanding flanges 18, 18 in 20 a plane transverse to the longitudinal direction of the end walls 14. In manufacture of plates in accordance with my invention, the said faces 17 of the plate, while prevented from bulging or bowing at their side 25 edges, are made to bulge or curve from side to side, and the top and bottom flanges are likewise arcuate in shape so as to maintain the curvature or bulging of the plate. It is found that by so doing, the devices increase 30 very materially in effectiveness. The probable cause is that the grid has a corresponding bulge and by bulging the plate also, the space or gap between plate and grid is kept closer to a constant. Obviously the bulge in 35 the opposite larger faces 17 results in the distance between the same increasing toward

the vertical center of the plate, but at any vertical section, all the distances between the plates will be the same.

It is to be particularly noted that while 40 I have shown one or two eyelets on each end wall and have shown reinforcement only at the outer edges of the larger faces of the plate, it is to be understood that the exact number or position of these parts is 45 not restricted to the precise showing. I deem it within the scope of the invention to both vary the number, size and position of these parts as may be found necessary or desirable. 50

Obviously other detail changes and modifications may be made in the manufacture of my improved electron discharge device, and I do not wish to be understood as limiting myself to the exact structure shown except 55 as set forth in the following claims when construed in the light of the prior art.

Having thus described my invention, I claim:

1. An electron discharge device having a 60 plate in the form of a four sided open ended box having two narrow and two broad sides said broad sides being slightly bulged and flanges on the bulged edges for strengthening said bulged sides. 65
2. An electron discharge device including a hollow plate member with four substantially rectangular sides two of which are bulged outwardly and flanged edges for reinforcing the whole member.

SYLVESTER W. CROWLEY
